UNITED STATES PATENT OFFICE.

JAMES BRUCE MACDUFF, OF BROOKLYN, NEW YORK.

STEERING-WHEEL SPINDLE FOR VEHICLE-AXLES.

No. 833,404.

Specification of Letters Patent.

Patented Oct. 16, 1906.

Application filed March 15, 1906. Serial No. 306,289.

To all whom it may concern:

Be it known that I, JAMES BRUCE MACDUFF, a citizen of the United States, residing at Brooklyn, in the county of Kings and State 5 of New York, have invented certain new and useful Improvements in Steering - Wheel Spindles for Vehicle-Axles; and I do declare the following to be a full, clear, and exact description of the invention, such as will enable 10 others skilled in the art to which it appertains to make and use the same.

My invention relates to improvements in vehicle-axles and their pivoted spindles for the steering-wheels; and it consists in the 15 novel construction, combination, and arrangement of parts hereinafter described and claimed.

The object of the invention is to provide a 20 knuckle-joint between the spindle and axle, by means of which the shock and vibration will be removed from the pivot-pin, so that the latter will be prevented from being wrenching or broken when the vehicle passes over a rough or uneven surface.

25 The above and other objects, which will appear as the nature of the invention is better understood, are accomplished by the construction illustrated in the accompanying drawings, in which—

30 Figure 1 is a plan view of a portion of one end of a vehicle-axle and its spindle pivotally mounted thereon by means of my improved knuckle-joint. Fig. 2 is a side elevation of the same. Fig. 3 is a vertical longitudinal 35 sectional view through the same. Fig. 4 is a vertical transverse sectional view taken on the plane indicated by the line 3-3 in Fig. 1; and Fig. 5 is a detail view of the end of the axle, showing the projecting bearing thereon.

40 Referring to the drawings by numeral, 1 denotes one end of a vehicle-axle, and 2 the spindle of one of the steering-wheels. These parts may be of any desired form and construction and pivotally connected in any 45 suitable manner; but, as shown, the spindle is mounted to turn or swing horizontally upon a vertical pivot 3, which passes through alining apertures in the spaced upper and lower arms 4 of the bifurcated end of the axle.

50 1 and an alining opening in the head or block 5 upon the inner end of the spindle 2, said head or block being disposed between the arms 4, as clearly shown in Fig. 3 of the drawings. The head or inner end 5 of the 55 spindle has formed or secured upon it an angularly-projecting arm 6, to which the usual

operating rod or link (not shown) is pivotally connected, so that the spindle 2 may be swung laterally or horizontally to steer the vehicle.

In order to relieve the pivot 3 of the shock, vibration, and strain to which it is subject when the vehicle passes over rough or uneven surfaces, I provide upon the axle 1 a suitable bearing 8 and upon the spindle 2 an extension 9, adapted to engage and coact with said bearing. As shown, the bearing 8 is in the form of integral projections 10 upon opposite sides of the axle 1 a short distance from its forked or bifurcated outer end; but it may be of any other form and construction, so that it has upper and lower bearing-surfaces 11 12, adapted to be engaged by the upper and lower plates or bars 13 14 of the extension 9. The latter is in the form of a V-shaped frame 15, which is formed integral with the head 5 of the spindle and is adapted to swing laterally or horizontally upon the axle which extends through it. This frame 15 comprises two inwardly-extending diverging side pieces 16, which project from the head 5 of the spindle and have the cross plates or bars 13 14 connecting their inner ends and secured thereto by bolts or similar fastenings 17, as clearly shown in the drawings. By 85 making the plates or bars 13 14 removable in this manner they may be removed and replaced when worn. It will be seen that as the axle 2 is swung for the purpose of steering the vehicle these upper and lower plates 13 14 will at all times bear upon the extended bearings 8 on the axle, and thereby relieve the pivot 3 of strain and greatly strengthen the connection between the spindle and axle.

From the foregoing description, taken in connection with the accompanying drawings, the construction, use, and advantages of the invention will be readily understood without requiring a more extended explanation.

Various changes in the form, proportion, and the minor details of construction may be resorted to without departing from the principle or sacrificing any of the advantages of the invention as defined by the appended claims.

Having thus described my invention, what I claim as new, and desire to secure by Letters Patent, is—

1. An axle, bifurcated at the end to provide spaced upper and lower arms, in combination with a spindle having a head at its inner end mounted between said arms, said

head having an extension provided with elements bearing and slidable on the upper and lower sides of the axle, and a vertical pivot for the spindle, extending through the arms 5 of the axle and the head of the spindle, substantially as described.

2. The combination with an axle and a spindle pivotally mounted thereon, of lateral projections upon opposite sides of said axle 10 having upper and lower bearing-surfaces, a V-shaped frame extending inwardly from said spindle and having upper and lower removable cross-bars to engage said bearing-surfaces.

3. The combination with an axle and a 15 spindle pivotally mounted thereon, of a bearing upon said axle, an extension upon said spindle, and removable elements upon said extension for engaging the upper and lower faces of said bearing. 20

In testimony whereof I have hereunto set my hand in presence of two subscribing witnesses.

JAMES BRUCE MACDUFF.
